UNITED STATES PATENT OFFICE.

HENRY L. KOEHLER, OF LOUISVILLE, KENTUCKY

PRINTING-PRESS.

1,103,147.

Specification of Letters Patent. Patented July 14, 1914.

Application filed July 2, 1912. Serial No. 707,235.

To all whom it may concern:

Be it known that I, HENRY L. KOEHLER, a citizen of the United States, residing at Louisville, in the county of Jefferson and State of Kentucky, have invented certain new and useful Improvements in Printing-Presses; and I do hereby declare the following to be a full, clear, and exact description of the invention, such as will enable others skilled in the art to which it appertains to make and use the same.

This invention relates to printing presses, and it relates more particularly to an improved rotary printing press.

An object of the invention is to provide an improved rotary printing press for printing on burlap, and especially on burlap bags and the like.

A still further object of the invention is to provide means whereby the bags are quickly, easily and accurately fed into the press.

A still further object of the invention is to provide an improved delivering mechanism for the press.

A still further object is to provide means for quickly relieving the pressure between the printing roller and the pressure roller.

A still further object is to provide an improved resilient mounting for the pressure roller.

A still further object is to provide a resilient cushion between the printing roller and the pressure roller.

A still further object is to provide improved means for securing the printing plates on the printing roller.

A still further object is to provide an improved ink feeding and ink distributing mechanism.

Other objects and advantages may be recited hereinafter and in the claims.

In the accompanying drawings, which form a part of this application, Figure 1 is a right side elevation of my improved rotary printing press, having my improved delivering mechanism attached. Fig. 2 is a left side elevation of my improved printing machine. Fig. 3 is a front elevation thereof. Fig. 4 is a rear elevation thereof.

Referring to these drawings, in which similar reference characters correspond to similar parts throughout the several views, the main frame of the machine consists of a right-hand support 15, a left-hand support 16, yoke supports 17 and a yoke 18, said yoke

supports and yoke supporting the inking mechanism, which will be hereinafter described. The several supports are held in vertical, parallel and spaced relation by means of struts 19 and a feed table or front table 20.

The printing roller 21 is mounted on a main shaft or printing roller shaft 22, the latter being journaled in bearings 23, which are fixed to the members 15 and 16.

A pressure roller 24 is carried by a shaft 25 which is mounted in bearings 26, said bearings being slidably seated in the recessed walls of the members 15 and 16, and being guided for vertical movement between the vertical guide elements 27. The bearing 26 is seated upon a resilient cushion 28, of rubber or the like, said cushion being carried by a flanged lifter plate 29.

The frame members 15 and 16 are depressed at 30 for the accommodation of a lifter cam 31 mounted on a lifter shaft 32, said shaft being seated in apertures through the depressed portions 30 of the frame. The top of the pressure roller is normally in the same horizontal plane with the top of the table 20, the rear end of said table extending into close proximity to said pressure roller.

In front of the table 20 a feed roller 33 is mounted on the shaft 34, said shaft being journaled in bearings 35, said bearing being adjustably secured to the frame members 15 and 16, as shown at 36, a set screw 37 being provided for the adjustment of the bearing relative to the frame. A feed belt 38 passes around the rollers 24 and 33, and shoulders 39 are provided on the roller 24 for guiding the belt 38. It is obvious that the belt 38 extends approximately throughout the length of the roller 24, or in other words, the width of the belt 38 is as great or greater than the width of the bag or other article to be printed, so that said article will not be dragged over a fixed surface, which might cause the same to be retarded, while being fed; and wrinkling or puckering of the article is thereby avoided. This belt is preferably made of resilient material such as rubber or the like, or of a composition of rubber and canvas, so that the pressure roller 24 is provided with a resilient coating between its outer surface and the printing roller.

In order to provide for quickly feeding the bags into the machine, I provide a pair of feed disks 40 which are preferably

2
 knurled on their convex surfaces, for preventing the bags from slipping. These disks are fixed on a shaft 41 which is rotatably mounted in lifter arms 42, said arms being fixed on a shaft 43, journaled in bearings 44, carried by brackets 45 which are secured on the frame. The arms 42 constitute forwardly extending elements of lifting levers of which the rearwardly extending arms 46 constitute other elements. The brackets 45 are made adjustable so that feed disks 40 can be made to bear on the feed belt at all times; but it is preferable that said disks be slightly raised at intervals, as shown. The rollers 47 are journaled at 48 to the rear ends of the arms 46, said rollers being operatively related to cams 49, fixed on the shaft 22, so that when the printing roller and shaft 22 are rotated, the cam 49 contacts with the roller 47 and depresses the rear end of the lifter lever, and thereby raises the feed disks, as shown. However, when the printing roller has moved through an angle of less than 45°, the roller 47 is released from engagement with the cam 49, so that the feed disks are allowed to descend, by gravity, so as to rest upon the sheet or bag while it is being conveyed between the printing roller and pressure roller.

At the rear of the pressure roller is an inclined delivery table 50, said delivery table being provided with a rabbet 51 into which the free end of the delivery fan 52 is adapted to be seated, a strip 53 of rubber or the like, being provided to cushion the fall of the fan into the rabbet.

The delivery mechanism may be either in the form of an attachment, or it may be made fixed and permanent with the printing press. This delivery mechanism consists of side arms, one of which is indicated by the numeral 54, said side arms being secured together by means of struts 55 and shafts 56 and 57. The shaft 56 carries the fan 52 and has a crank 58 fixed thereon, said crank carrying a roller 59 which is adapted for movement longitudinally of a channeled arm 60, so that when the arm 60 is swung on the shaft 57, the crank 58 is thereby swung through an angle of approximately 180° or into approximately horizontal position; so, it will be seen that, when the bag which has been printed slides upon the fan 52, the fan will swing rearwardly and deposit the bag in horizontal position. In order to operate the delivery mechanism at the moment when the bag is in proper position thereon, the actuating means for the delivery mechanism must be properly timed with relation to the time when the printing operation has been completed. This actuating mechanism consists of a delivery actuating lever 61, pivoted at 62 to the frame and being pivotally connected at

63 to a link 64, the latter being pivoted at 65 to the lever 60. The upper end of the lever 61 carries a roller 66 which is cooperatively related to a cam 67, secured on the shaft 22. In order to properly time the movement of the delivery mechanism with that of the printing mechanism, it is only necessary to slightly rotate the cam 67 upon the shaft 22 and to secure it in adjusted position by means of a set screw 68. The frame 54 is removably secured upon the frame members 15 and 16 by means of studs 15' and 15", the latter constituting extensions of the rod 19, the frame 54 being provided with slots 54' and 54" which may be easily passed over the shanks of the studs 15' and 15", so that the delivery mechanism may be quickly and easily removed and replaced.

The frames 15 and 16 are provided with a buffer 15^b of rubber or other suitable material, for stopping the rearward movement of the lower end of the lever 61, and for limiting the downward movement of the fan 52. The slot 74 can either be in additional bracket 73 or in main arch 18.

The inking mechanism consists of a tank or receptacle 69, for containing a supply of ink; a feed roller 70 being located therein, a transfer roller 71, mounted upon a shaft 72, said shaft being carried by a bracket 73 and adapted for transverse movement in a slot 74 of the bracket; an ink distributing roller 75, loosely mounted on the main drive shaft 76; roller shifters 77, pivotally mounted at 77^a to the frame, for shifting the roller 75 on the shaft 76; cams 78, secured on the shaft 76 and adapted to move the shaft 72 in the slot 74, so as to contact alternately with the feed roller 70 and the distributing roller 75, and to apply ink on the latter which carries the ink to an inking roller 79, mounted on the shaft 80, and adapted to contact with the type or printing plates on the printing roller 21. The ink reservoir or tank 69 is provided with thumb screws 81 for regulating the quantity of ink fed by the feed roller.

The shifter 77 is provided with rollers 82 and 83. The rollers 82 are adapted to contact with the respective ends of the roller 75, the rollers 83 being in the path of cams 84 which are formed on the respective ends of the printing roller or drum 21. These cams 84 are both arcuate and wedge-shaped, as shown in Figs. 1 and 3 respectively. The feed roller 70 is actuated intermittently by means of a ratchet wheel 70', a pawl 70", a link 70^b and a crank pin 70^c. This crank pin is adjustably mounted in a slot 70^d, formed in the member 70^e, said member being secured on an end of the main drive shaft 76. The link 70^b and the pawl 70" are pivoted to an oscillatory arm 70^f, journaled on the feed roller 70; so that, with each revolution of the shaft 76, the arm 70^f is drawn

down and pushed up, thereby causing the pawl 70^a to engage a different tooth of the ratchet 70', and to rotate the roller 70 quickly, to the distance of one tooth. It is 5 obvious that, by providing the ratchet 70' with more teeth and adjusting the position of the crank pin 70^c, the degree of rotation of the roller 70 may be regulated, by adjusting the position of the crank pin 70^c relative to the member 70^a.

10 In operation, power is applied, from any proper source, to the pulleys 85 and it is transmitted through the shaft 76, to the inking mechanism. A gear wheel 86 is secured 15 on the shaft 76 and meshes with a gear wheel 87, mounted on the frame, and this gear wheel 87 meshes with a gear wheel 88, which is secured on the shaft 22 and coacts therewith for rotating the printing drum and for 20 raising the feed disks 40, through the medium of the arms 42 and 46, the roller 47 and the cam 49. The gear wheels 86, 87 and 88 constitute a train of gears which coact with another gear wheel 89, secured on 25 the shaft 25, for actuating the pressure roller 24. It will be seen that the ratio of the pitch diameters of the gears 88, and 89 is approximately equal to the ratio of the diameters of the printing roller and pressure 30 roller respectively; so that the circumferential speed of the faces of the printing plates, on the printing roller, is equal to the circumferential speed of the pressure roller. Therefore, when a bag or the like is carried 35 between the printing roller and pressure roller, blurring of the printed matter is avoided.

It may sometimes occur that a bag will be started into the press, between the feed roller 40 and feed disks, and after the disks have descended upon the bag, it may be discovered that the bag has been improperly placed, or that the bag is wrinkled, or for some other reason it is undesirable for the bag to 45 pass between the printing roller and pressure roller. In such an event, the operator should grasp the rod 41 and lift the disk 40, so that the bag could be easily withdrawn. This may be quickly and easily accomplished 50 because of the free movement of the arms 42 and rollers 47, said rollers not being in engagement with the cams 49, but merely in contact therewith. However, it may occur that a bag or the like has been fed into the 55 machine and has started between the pressure roller and printing roller, whereupon it may be discovered that the bag contains or is connected with something which would be detrimental to the printing roller or pressure roller if allowed to pass therebetween; and in such an event it would be necessary to 60 increase the space between the rollers 21 and 24, so that pressure would be relieved and the detriment thereby avoided. In order to 65 accomplish this result, I have journaled the

shaft 25 in the vertically movable bearings 26, and have provided the lifter 31, as described in the foregoing. The shaft 32 extends approximately the entire length of the machine and through both of the depressed 70 portions 30, and carries one of the cams 31 on each of its ends, so that when one of the lifters or cams 31 is actuated, the other is also actuated through the medium of the shaft 32. These lifter cams are actuated by 75 means of a hand lever 90 and a link 91 positioned at one side of the machine, said link being pivoted at 92 to the cam 31, and at 93 to the lever 90; a latch 94 and a toothed segment 95 being provided for regulating 80 the adjustment of the lever 90 and the cam 31, and at the opposite side of the machine the link 91 has one of its ends pivoted to the cam 31 at 92' and the other end pivoted at 93' to the swinging link 94' so that the pressure between the printing roller and the pressure roller may be regulated or annulled, at the will of the operator. The teeth of the gear wheels 88 and 89 are made relatively 85 long, so that said gear wheels are always in 90 mesh, even when the pressure roller is at its lowest position.

As a means for securing the type or printing plates on the roller or drum 21, I have provided the same with under-cut peripheral channels 21' and have provided oppositely disposed notches 21^a in the sides of the channels 21'. I have also provided retaining strips or plates 21^b which are provided with flared or downwardly converging lugs which are adapted to be inserted into the notches 21^a and thence into the slots 21' between the notches. The sides of the strips 21^b are rabbeted, so as to form overhung flanges. In practice, the printing plates (not shown), are provided with flanges on their opposite edges, which are adapted to extend under the flanges of the strips 21^b, and the number of retaining strips 21^b is approximately in proportion to 100 the number of printing plates secured on the printing roller or drum; one more retaining strip being required than the number of printing plates secured thereby.

It will be seen that I have provided a 115 machine of this character which is fully capable of attaining the foregoing objects, and in a thoroughly practical and efficient manner.

I do not limit my invention to the exact 120 details of construction, combination, and arrangement of parts, as illustrated and described, but my invention may only be limited by a reasonable interpretation of the claims.

I claim:—

1. A printing press providing a main frame having vertical side members, vertical guides thereon, a printing roller journaled in the frame, a pressure roller, bear- 130

- ings for the same having sliding engagement with said guides, resilient blocks under said bearings, lifter plates under said resilient blocks, a shaft journaled in the frame under said pressure roller, cams secured on said shaft and adapted to bear against said lifter plates for lifting said pressure roller against said printing roller, and actuating means for said cams.
- 10 2. A printing press providing a main frame having vertical side members, vertical guides thereon, a printing roller journaled in the frame, a pressure roller, bearings for the same having sliding engagement with said guides, resilient blocks under said bearings, lifter plates under said resilient blocks, a shaft journaled in the frame under said pressure roller, cams secured on said shaft and adapted to bear against said lifter plates for lifting said pressure roller against said printing roller, and actuating means for said cams.
- 15 3. A printing press providing a main frame having vertical side members, vertical guides thereon, a printing roller journaled in the frame, a pressure roller, bearings for the same having sliding engagement with said guides, resilient blocks under said bearings, lifter plates under said resilient blocks, a shaft journaled in the frame under said pressure roller, cams secured on said shaft and adapted to bear against said lifter plates, and means for actuating said cams for simultaneously lifting said pressure roller and said feed belt against said printing roller.
- 20 4. A printing press providing a main frame having vertical side members, vertical guides thereon, a printing roller journaled in the frame, a pressure roller, a resilient feed belt embracing said pressure roller and operated thereby for feeding articles to said printing roller, bearings for the pressure roller having sliding engagements with said guides, resilient blocks under said bearings, lifter plates under said resilient blocks, a shaft journaled in the frame under said pressure roller, cams secured on said shaft and adapted to bear against said lifter plates, and means for actuating said cams for simultaneously lifting said pressure roller and said feed belt against said printing roller.
- 25 5. A printing press providing a main frame having vertical side members, vertical guides thereon, a printing roller journaled in the frame, a pressure roller, bearings for the same having sliding engagement with said guides, resilient blocks under said bear-

ings, lifter plates under said resilient blocks, a shaft journaled in the frame under said pressure roller, a feed belt surrounding said pressure roller, cams secured on said shaft and adapted to bear against said lifter plates for lifting said pressure roller and said feed belt against said printing roller, and actuating means for said cams.

4. A printing press providing a main frame having vertical side members, vertical guides thereon, a printing roller journaled in the frame, a pressure roller, a resilient feed belt embracing said pressure roller and operated thereby for feeding articles to said printing roller, bearings for the pressure roller having sliding engagements with said guides, resilient blocks under said bearings, lifter plates under said resilient blocks, a shaft journaled in the frame under said pressure roller, cams secured on said shaft and adapted to bear against said lifter plates, and means for actuating said cams for simultaneously lifting said pressure roller and said feed belt against said printing roller.

In testimony whereof I have signed my name to this specification in the presence of two subscribing witnesses.
